IRONING COVER FOR SEWING MACHINE LID
Sandra Cournoyer, 2457 Fernandez Drive, Sacramento,
Calif.Filed Aug. 6, 1964, Ser. No. 387,973
2 Claims. (Cl. 38—140)

This invention relates to a cover for a sewing machine lid and more particularly to a means for transforming the opened lid of a sewing machine into an ironing surface.

A primary object of this invention is the provision of a device of the type described which is sturdy and durable in construction, reliable and efficient in operation, and relatively simple and inexpensive to manufacture and maintain.

Another object of this invention is the provision of a cover for a sewing machine lid which includes a scorch proof material covering the upper surface of the lid when the lid is disposed in its opened position to permit the seamstress to press or iron the material on which she is working without having to move to a separate ironing board.

A further object of the instant invention is the provision of an ironing cover for a sewing machine lid which can be maintained on the lid when the lid is moved to its closed position providing a decorative surface for the sewing machine cabinet.

Yet another object of this invention is the provision of such a device wherein separate decorative means may be removably secured to the upper surface of the ironing cover when the lid of the sewing machine cabinet is in its closed position.

Other and further objects reside in the combination of elements, arrangement of parts, and features of construction.

Still other objects will in part be obvious and in part be pointed out as the description of the invention proceeds and as shown in the accompanying drawing wherein:

FIGURE 1 is a side elevational view of a conventional sewing machine cabinet having a cover in accordance with the instant inventive concept carried by its lid, the opened position of the lid being shown in dotted lines; and

FIGURE 2 is a transverse cross-sectional view taken substantially on line 2—2 of FIGURE 1 with a removable decorative means being shown in dotted lines.

Like reference characters refer to like parts throughout the several views of the drawing.

Referring now to the drawing, a conventional sewing machine cabinet is designated generally by the reference numeral 10 and is comprised basically of a plurality of legs 12, a hingedly carried support 14 movable from the closed position shown in full lines to the dotted position shown at 14' in dotted lines, and a lid 16 movable from the closed position shown in full lines to the opened position shown at 16' in dotted lines. In the closed position of the lid it overlies the sewing machinery (not shown) for protection of the same and in the opened position it exposes the same for use in a conventional manner, a knee operated control means for the sewing device being shown at 18.

The covering of the instant invention is designated generally by the reference numeral 20 and may be made of any desired material to be slidably received over the lid 16, at least the portion of a covering 20 disposed on top of the lid 16 when the lid is in the opened position being

2

formed of a scorch proof material to define an ironing surface. Preferably, the covering 20 is formed of three layers bonded or otherwise secured together in any conventional manner such as by seams 22 to define a pocket for slidingly engaging over the lid 16. The individual layers may vary within the scope of the instant inventive concept, but the inner layer 24 is preferably formed of a relatively soft, non-marring furniture engaging material which may be either a conventional fabric such as a cotton-rayon material or a non-slip foam material such as a polyester or a polyurethane foam material. The intermediate layer 26 is preferably fireproof or non-flammable and may be formed of either a fiberglass or an asbestos compound. The outer scorch proof layer is preferably impregnated with a lubricating or easy glide substance such as Teflon to facilitate moving an iron thereacross.

The portion of the covering 20 disposed on top of the lid 16 when the lid is in its closed position may include any conventional decorative means to render the same attractive in appearance whereby it may be maintained on the lid even when the sewing machine is not being utilized. This may merely include a printed or painted design or it may incorporate a removably secured decorative means such as the artificial floral arrangement shown at 30. If desired, this decorative means may be removably secured to the covering 20 in any conventional manner such as by the snaps 32 shown in FIGURE 2 whereby it may be readily replaced by other decorative means to vary the same or to more readily fit in with the decor of the room in which the sewing machine is utilized.

The use and operation of the device of the instant invention will be apparent from the above description.

It will now be seen that there is herein provided an improved ironing cover for sewing machine lids which satisfies all of the objectives of the instant invention, and others, including many advantages of great practical utility and commercial importance.

Since many embodiments may be made of this inventive concept, and since many modifications may be made of the embodiments hereinbefore shown and described, it is to be understood that all matter herein is to be interpreted merely as illustrative, and not in a limiting sense.

I claim:

1. A covering specifically adapted for use with the lid of a sewing machine cabinet foldable from an open position exposing a sewing machine for use and a closed position overlying the sewing machine for protection, said covering comprising a first surface and a second surface, said first surface when said lid is in open position comprising an upper ironing surface, and said second surface comprising a top covering when the lid is in closed position, said surfaces being stitched together along three sides, the fourth side being open to define a pocket adapted to be slipped over said lid, fastener means on said second surface, and a decorative element releasably secured to said fastener means for exposure on the top of the sewing machine when the lid is in closed position.

2. The structure of claim 1 wherein said first and second surfaces are each comprised of three layers, an inner layer comprised of a relatively soft non-marring furniture engaging material including a non-slip polyurethane foam material, an intermediate layer of fireproof non-flammable fiberglass, and an outer layer of scorch-proof material impregnated with Teflon to facilitate moving an iron thereover.
